LLP

(57) **CLAIM**

The ornamental design for a coil spring as shown and described.

DESCRIPTION

FIG. 1 is a front perspective view of a coil spring;

FIG. 2 is a left side view thereof;

FIG. 3 is a front view thereof;

FIG. 4 is a right side view thereof;

FIG. 5 is a rear view thereof;

FIG. 6 is a top view thereof; and,

FIG. 7 is a bottom view thereof.

The broken dash lines shown in the drawing views represent non-claimed subject matter, and neither the lines themselves nor anything within the lines form any part of the claimed invention.

1 Claim, 3 Drawing Sheets
